[57] **ABSTRACT**

A process of cold rolling sheets in strip form under tension, preferably on a beam backed cluster mill while automatically controlling roll pressure distribution across the strip, so that strip tension is uniform all the way across the strip. Static air pressure is applied against the strip to deflect away from the pass line. Any unevenness in strip tension results in an uneven deflection, which in turn produces variations in the rate of flow of air escaping through clearances in the deflecting instrumentalities which affects their internal air pressure. Those differences are employed directly to operate the roll pressure distribution in the mill. "On" and "off" timing of the control mechanism avoids complex instrumentation and provides maintenance-free operation.

When tension at any spot transversely of the strip drops to zero thus heralding the formation of a cobble, the apparatus actuates a wedge which stops the strip instantly, leaving no material from which to form a cobble.

Pulsating air pressure which is inherently associated with the use of volumetric blowers is further utilized to produce high frequency rhythmic variations in strip tension, preferably opposed in phase as to the strip segments ahead and behind the work rolls. This reduces the roll separating force and permits substantially heavier reductions per pass.

Apparatus for performing the process is also disclosed.

FIG. 6

PROCESS AND APPARATUS FOR PRODUCING METAL SHEETS OF BETTER FLATNESS

BRIEF SUMMARY OF THE INVENTION

Beam backed multi-roll mills for rolling flat articles such as are shown, for example, in U.S. Pat. No. 2,479,974, provide for instantaneous change of the roll profile by controlling the height of the spaced roll supports. This produces an increase or decrease in work roll pressure at any point across the face of the roll and thus makes it possible to produce a flat strip of raw material of not quite uniform thickness and temper.

Typical flatness defects such as edge waves and "pockets" result from too great a roll pressure applied in certain areas, and flatness can be corrected by suitably adjusting the corresponding roll supports. Since a tension strip appears flat to the eye during rolling, apparatus has been provided in the past to measure the distribution of tension across the strip during rolling, usually by exerting a deflecting force against the strip and placing proximity meters at various points across the strip to measure the deflection. A high deflection indicates low tension.

Such proximity meters of sufficient accuracy and small time lag are usually complex electronic devices; and an attempt to use the indications of such meters automatically to operate the controls of effective height of the spaced roll supports, leads to apparatus of great complexity and greatly increases the maintenance difficulties under mill conditions.

The present invention also involves the use of uniform pressure applied normally to the strip surface, preferably at points corresponding to the spaced roll supports, but in such a manner that the deflecting instrumentality functions at the same time as a meter of strip tension at that spot and also as an automatic actuator of the effective height of that particular spaced roll support. Another benefit flowing from the present invention provides an improvement in the rolling action of the mill itself as will become clear from the description hereinafter.

BRIEF DESCRIPTION OF THE SEVERAL VIEWS OF THE DRAWING

FIG. 1 is a side elevation partly in section of one embodiment of the present invention.

FIG. 2 is a side elevation partly in cross section taken on the line 2—2 of FIG. 3, showing the invention applied to a simplified mill.

FIG. 3 is a cross sectional view taken on the line 3—3 of FIG. 2.

FIG. 4 is a schematic view of certain details of FIG. 2.

FIG. 5 is an enlarged detailed view of one of the pressure pots and its associated gauge system.

FIG. 6 is an elevational view of another embodiment of the invention.

DETAILED DESCRIPTION

Reference may be had to the Sendzimir U.S. Pat. No. 2,479,974 for a detailed description of a typical beam backed multi-roll mill having means to adjust the roll profile. In FIG. 1 the present invention is shown in connection with a so-called "20-Hi" mill while in FIG. 3 and FIG. 6 it is shown in connection with a so-called "6-Hi" mill. It should be understood that the 6-Hi mill has been shown for simplicity and ease of understanding; but the same principles may be applied to the

20-Hi or other cluster mill in which case the screwdown mechanism shown in FIG. 3 is applied to the two central ones of the beam backed backing rolls.

Referring to FIG. 1, a strip 1 is shown being cold rolled in a mill 2 with strip tension being applied by the unwinder 3. The strip passes from the unwinder over a deflector roll 4 and thence horizontally into the mill 2.

For ease of understanding, reference will now be made to FIG. 2 and 3 showing the "6-Hi" mill. In this mill, spaced supports 5 are provided for the shaft 9 which carries the backing bearings 8. The supports 5 rest in troughs machined into the housing beam 2' for rigid support. Eccentrics 6 are disposed inside the supports 5 and are free to rotate upon the shaft 9 and are individually rotated by pinions which are integral with the eccentrics and which engage racks 7. The position of the racks 7 is in turn controlled by the worm nut and screw 7' and driven by motors 7'' which have worms mounted on their shafts to turn the worm nuts and thereby raise or lower the racks 7. It will be clear that as the racks move up or down they engage the opposed gear segments of the eccentrics 6 and by rotating the eccentrics 6 adjust the vertical position of the backing bearings 8 and thus the vertical position of the work roll which is supported thereby.

In the drawings, the screwdown mechanism has been shown as applied to the lower set of rolls whereas in actual practice, the lower set of rolls are adjustable only for opening the roll bite for threading and the screwdown is generally applied to the upper rolls. However, for purposes of describing the invention, it makes no difference whether the screwdown is applied to the upper or lower rolls.

It will be clear now that by energizing one or more of the motors 7'', the respective bearings 8 may be raised or lowered, whereby to control roll pressure in the vicinity of each of the supports 5.

Control of the motors 7'' is provided by means of apparatus which will now be described. Aerostatic pressure is applied against the strip 1 preferably by means of pressure pots 10. These are shown schematically in plan view in FIG. 4 in relation to the positions of the spaced supports 5 of FIG. 2. They are identified in the drawing by I to VII inclusive. The several pressure pots 40 are rigidly mounted on the beam 11 (FIG. 5) which is provided with a wedge mechanism 35 at each end in order to align the row of pots 10 with the mill passline. Each of the pots is provided with a cup lip 10' in threaded engagement with the cup 10 so that the position of the lip may be adjusted accurately in relation to the strip 1. Air is supplied in equal quantities by the individual fixed displacement blowers 13 which are rotated by a common motor 13'. So long as the clearances between the several cup lips 10' and the strip 1 45 remain identical, the volume of air escaping through them will be the same and therefore the pressures in the pots 10 which provide for the deflection of the strip 1 will also be the same.

If now the central portion of the strip 1 is overrolled (the trade expression is "it has a pocket"), the tensioned strip still looks perfectly flat to the operator, but the thus locally diminished tension causes the clearances at the two corresponding pots III and IV to be more than the clearances at the other pots, and therefore their static pressure would be reduced.

Associated with each pressure pot there is a mercury column type of pressure gauge 14 which is shown in more detail in FIG. 5. This device according to the

present invention serves directly to control the motors 7" and thus automatically to correct any local over- or under-rolling so as to produce strips of good flatness. Air pressure from the pot 10 acts upon the mercury column 34' and any pressure fluctuations in the pot 10 will move the mercury to or from the columns 34a and 34" to balance with atmospheric pressure. Adjustable height insulated electrodes 14', 14" and 14a are provided for the respective mercury columns. These are disposed above the mercury level and their contact with the mercury actuates the corresponding motors 7" to raise or lower the respective screws 7 as the case may be.

In order to prevent over-control or hunting, it is preferred to energize the entire system (i.e., admit electric current to it) for short periods of time only by the use of any well known clock-type switch. An "on" period of a half second followed by a "off" period of ten seconds is practical for medium speed mills. In this way, in the case discussed above, if the half second correction has not changed the roll pressure in the areas controlled by the pots III and IV sufficiently, the next ten seconds will be spent measuring the new air pressures and if they are still not within permissible limits, another half second correction will automatically follow. On faster mills the ten second lingering periods may be reduced. Also faster response motors, for example, hydraulic, would permit a reduction in the half second adjustment periods.

Air supplied by displacement blowers inherently produces a pulsating stream of air and for this reason the needle valve 16 is provided to throttle the flow of mercury in the pressure gauge 14 so that it indicates the average static pressure in each pot 10 and only the average pressure therefore controls the action.

Unexpectedly, however, a further advantage results from the high frequency rhythmic vibrations in strip tension in that it makes it possible to take heavier pass reductions than when the tension is steady. This effect may be increased by tuning the frequencies and phases of the strip sectors on the up stream and down stream sides of the roll bite respectively so as to be synchronous but reversed in phase, so that the maximum tension ahead of the rolls corresponds to minimum tension behind the rolls. In order to produce these resonant vibrations, the deflector rolls 4 are mounted on slides and are provided with motorized screws 17 to obtain the optimum length of vibrating strip 1. This may be either a single wave form or a half wave with a node half-way or even shorter. Each wave leaves a slight but distinguishable mark on the surface of the strip and these marks almost disappear if they are small enough. If they have not disappeared, it may be necessary to make a final pass as an iron-out pass taking only the regular reduction and without use of the vibration principle.

The vibrations described above have another beneficial effect in that the strip comes out flatter by itself which makes it easier to produce a nearly perfect flatness of the strip. Yet another advantage is that a higher front tension in relation to the back tension may be used since the vibrations yield maximum benefits of back tension and therefore the excess of front tension can be used to assist the drive of the work rolls and thus take a bigger roll pass without strip slippage. This is important when small diameter work rolls are used.

An alternative embodiment of an apparatus useful in the pursuit of the present process is shown in FIG. 6. This is particularly useful for slower mills operating at

1,000 feet per minute and below which are used chiefly for expensive alloys rolled to light gauges where the operator's skill in coping with metallurgical requirements to obtain the desired quality is essential. Here the strip is subjected to a relatively much lower static pressure but the pressure extends over a very large area. As seen in FIG. 6, a pressure box 20 is shown extending lengthwise of the strip between seals at the deflector roll 4 and the wiper roll 19 which are very close to the work roll. Laterally, the pressure box 20 extends between two lateral fences adjustable for strip width and providing a small clearance between the upper lip of the fence and the edge of the strip through which air from the pressure box 20 is free to escape. The air is replenished and maintained at the required pressure by outside means such as one or more blowers 21. It may be observed that the pressure in the pots 10 in this embodiment is negative with respect to the box 20, but is still positive with respect to atmosphere.

Static pressure as low as a few ounces per square inch is usually sufficient to deflect the strip a considerable amount. If the deflection is only one percent of the length of the pressure chamber, flatness defects such as wavy edges or full centers or other irregularities can be directly and visually detected if the light is played on the strip at the correct angle for the operator. The operator therefore has the advantage in being able to check the effect of the automatic flatness control and if he see fit, to take over manually in particularly stubborn cases.

While these relatively large deflections can be measured by various simple means, it is still preferred to provide a cross beam with the bank of pressure pots 10 just as described in connection with FIGS. 1 to 5, except that air escapes from the pressure chamber 20 into the pot 10 and from there through equalized calibrated outflow valves 22 into the atmosphere. Here again in areas where the clearance between the lip of a pot 10 and the strip increases indicating stronger tension, the pressure inside the pot will decrease and vice versa. This change in pressure is then utilized to directly activate the flatness control elements as described in connection with FIGS. 1 to 5.

Another important advantage of the process and apparatus herein disclosed is that it makes it possible to protect the mill against one of the costliest accidents which can occur, known as a cobble. If a strip with an undetected side crack enters the roll bite, the portions of the strip on both sides of the crack will, of course, have lost their tension and the tension is then concentrated in the strip where the crack is deepest. That in turn causes the tensionless portion of the strip material entering the roll bite to fold over and form a so-called harmonica which produces crushing pressures against that spot of the work roll and renders it useless in a fraction of a second. Furthermore, since the uncracked portion of the strip continues to be rolled, it drags more of the harmonica into the roll bite and causes further damage which extends to the backing rolls and bearings.

Since the cause of each cobble is a tensionless portion of the strip and since according to the present invention this condition can be determined instantaneously, although it may be only be milliseconds before the accident, an emergency mill stop or screwdown opening device may be provided for instantaneous operation. Referring back to FIG. 5, there is provided a special leg 34a in the pressure gauge 14 and it is pro-

vided with an electrode 14a which is adjusted to switch the current on when the pressure in any pot drops to or near zero. The current to the electrode 14a is "on" continuously and is not periodically interrupted as was the case with the electrodes 14' and 14''. This is because the cobble may occur at any time.

For faster protection of the mill it is preferred to stop the advance of the strip through the mill instantly and thus not to give the rolls any material from which to form the harmonica. Thus, in FIG. 6 a gate is provided through which the strip passes ahead of the rolls and which consists of a frame including a lower beam 24' having a wedge surface and an upper beam 24. Associated with the beam 24' is a wedge block 23 operated by air cylinders 26 to push the wedge block 23 along the wedge surface of the beam 24' into the above mentioned gate when the cylinders 26 are actuated for example by a solenoid valve energized by the electrode 14a of FIG. 5.

During rolling the strip 1 may pass through the gate with ample clearance, but when a cracked strip approaches and any of the electrodes 14a detects the loss of strip tension, the wedge 23 is substantially instantaneously pushed into the gate over the tapered face of the beam 24' along with the strip itself which incidentally helps to push the beam 23 tighter and stops the progress of the strip by gripping it between the members 23 and 24. The undersurface of the beam 24 and the upper surface of the wedge member 23 may be serrated to enhance the stopping action. The immediate sharp increase of tension resulting from the coaction of the block 23 and 24 causes the strip to break in the roll-bite and it is then only necessary to stop the inertia of the two winders and the mill itself. During this operation, some strip may become unwound but damage to the mill is effectively avoided.

It will be understood that the disclosure herein is by way of example only and that various modifications may be made without departing from the spirit of the invention. No limitation not expressly set forth in the claims is intended and no such limitation should be implied.

The embodiments of the invention in which an exclusive property or privilege is claimed are defined as follows:

1. In the tension rolling of metal strip in a mill having work rolls and a deflecting roll, wherein the strip passes from the deflecting roll to the work rolls of a mill, the method of producing strip of improved flatness while avoiding the danger of scratching the surface by contact with any instrumentality, which includes the steps of applying a uniform deflecting pressure to a plurality of areas of equal size and shape disposed transversely of the strip, said areas being defined by the projections, on the strip, of the perimeters of a number of pressure pots located close to, and parallel to, said strip, adjustably mounting said pots to maintain a fixed position relative to the strip, by causing equal volumes of air to pass between the boundaries of said areas and the strip surface, thus producing a pressure differential between the inside and outside of said areas; the said pressure differential being uniform for all areas so long as the strip deflections are uniform, but varying when said deflections are not uniform, and adjusting the roll pressure transversely across the strip to restore the uniformity of said deflections when they vary.

2. The method of claim 1, wherein said air under pressure is caused to pulsate, and including the steps of

deflecting the strip similarly on the exit side of said mill by pulsating air pressure, and timing the frequencies and phases of the portions of strip on the entrance and exit sides of the mill to be synchronous but reversed in phase, whereby heavier than normal pass reductions may be achieved.

3. The method of claim 1, including the step of causing a major decrease in tension at any of said locations, indicating the formation of a cobble, to stop further motion of said strip substantially instantaneously, to prevent damage to said mill.

4. In a beam-backed cluster mill having rotating backing elements between each work roll and said backing beam, spaced across the work roll face, and adjustable supports between each two of said backing elements; a row of non-contacting pressure pots for deflecting the tensioned strip across its full width, means to supply air under pressure to said pots, the rims of said pots being disposed closely adjacent the strip to be rolled, a pressure gauge for each pot, said pressure gauges including electrical switching means for completing an electrical circuit upon a predetermined increase and decrease in pressure at the related pot, said circuit including the related motor means, said switching means comprising two interconnected columns of mercury, and a vertically adjustable electrode for each column, whereby upon the increase in pressure the mercury will rise in one of said columns and make contact with the related electrode, and upon a decrease in pressure the mercury will rise in the other of said columns and make contact with the related electrode.

5. In a beam-backed cluster mill having rotating backing elements between each work roll and said backing beam, spaced across the work roll face, and adjustable supports between each two of said backing elements; a row of non-contacting pressure pots for deflecting the tensioned strip across its full width, means to supply air under pressure to said pots, the rims of said pots being disposed closely adjacent the strip to be rolled, the air supply means being a pulsating one, and like deflecting instrumentalities being similarly disposed on the exit side of said mill, there being also a deflector roll on said exit side, said deflector rolls being adjustable toward and away from the work rolls of the mill, whereby the frequency and phase of the portions of the strip on the entrance and exit sides of the mill may be tuned to be synchronous but of opposite phase, to permit the achievement of heavier than normal pass reductions.

6. In a beam-backed cluster mill having rotating backing elements between each work roll and said backing beam, spaced across the work roll face, and adjustable supports between each two of said backing elements; a row of non-contacting fluid pressure means for deflecting the tensioned strip across its full width, means for controlling roll pressure across the strip to maintain uniform the resulting strip deflections, parallel beams above and below the strip on the entrance side of the mill, one of said beams having a sloping surface, a wedge block arranged to move on said sloping surface, power means to move said wedge block, cobble cause sensing means associated with each of said fluid pressure means, and an operative connection between said cobble cause sensing means and said power means, whereby upon the occurrence of a cobble causing event said wedge block, in cooperation with the opposed beams, will instantaneously stop the strip and prevent said cobble from damaging the mill.

7. In a beam-backed cluster mill having work rolls and a deflector roll spaced a substantial distance in advance of said work rolls, and having rotating backing elements between each work roll and said backing beam, spaced across the roll face, and adjustable support between each two of said backing elements; a pressure box extending substantially over the entire width of the strip being rolled, and extending over the major portion of the length of the strip between said deflector roll and said work rolls, for deflecting the ten-

10

sioned strip across its full width, a roll of non-contacting pressure pots having rims adjustable disposed closely adjacent the strip to be rolled, the pressure in said pots being negative with respect to the pressure in said pressure box but positive with respect to atmosphere, and means to detect pressure fluctuations in said pots due to differences in the escape of air from said pressure box into said pressure pots.
